BUTTON SEWING MACHINE

Michael McCann, Ozone Park, N. Y., assignor to
 The Singer Manufacturing Company, Elizabeth, N. J., a corporation of New Jersey

Application April 3, 1936, Serial No. 72,460

12 Claims. (Cl. 112—114)

This invention relates to button-clamps for button sewing machines, and it has as its primary object to provide an improved clamp which will more securely hold shank buttons than clamps heretofore available; which is adjustable to accommodate buttons of various types and sizes; which is self-locking and therefore cannot be opened inadvertently by accidental movement of the button; and which readily may be used in conjunction with various types of work-supports, whereby the buttons may be attached by either through-and-through or blind stitches and either with or without stay buttons.

These objects have been attained by the provision of a button-clamp having a supporting arm, a plurality of interchangeable button-supporting feet adapted selectively to be secured thereto, each foot having a recess designed to receive a different type of button-shank, and a two part button-holding lever pivotally mounted on said supporting arm and adapted to engage a button to hold the shank thereof in the recess in the supporting foot. One part of the button-clamping lever is adapted to have the other part movably mounted thereon. The latter part may comprise any one of a plurality of interchangeable button-holding arms each provided with a cup-like button-engaging portion, which portions vary in shape and size to conform to the shape and size of different sizes and types of buttons to be held. Due to the adjustability of the button-holding portion of the lever and the shapes and sizes of the various cup-like button-engaging portions, multiple point contact, full surface contact or two line contact, at diametrically opposite sides of the button, may be obtained between the button and the arms, as distinguished from the single point contact and single line contact of prior button-clamps. Thus the present clamp more securely holds the buttons and more effectively prevents movement thereof in the button-clamp.

The self-locking feature of the clamp is obtained by the specific connection between the button-clamp lever and its actuating lever as hereinafter will be explained.

Other objects and advantages will be in part indicated in the following description and in part rendered apparent therefrom in connection with the annexed drawings in which:

Figure 1 is a side elevation of a Singer Class 175 button sewing machine embodying the present invention.

Fig. 2 is an enlarged, left end elevation of a portion of the machine illustrated in Fig. 1, showing the present improved button-clamp fitted with

a button-supporting foot, adapted to receive the wire shank of a so-called military button, operating in conjunction with a work-support designed so to hold the work that the button is secured by blind stitches. 5

Fig. 3 is a plan view of the parts shown in Fig. 2, omitting the needle-bar, needle, and the lower portion of the bracket-arm head.

Fig. 4 is a view similar to Fig. 2 showing the improved button-clamp fitted with a button-supporting foot designed to receive a leather shank button, with a button-holding arm having a cup-like button-engaging portion designed to receive a smaller button, and with the work-plate of the machine fitted with a work-support adapted to hold a stay button, whereby the button and stay button are attached to the work simultaneously by through-and-through stitches. 10

Fig. 5 is a view similar to Fig. 4 but showing the button-clamp fitted with a button-supporting foot 20 designed to receive a self-shank button, with a button-holding arm similar to that shown in Fig. 2, and with the machine fitted with still another form of work-support adapted for blind stitching.

Fig. 6 is a diagrammatic view illustrating the 25 self-locking feature of the present improved button-clamp.

Referring more specifically to the drawings, the invention is disclosed as applied to a button-sewing machine comprising a supporting base 1, 30 a bed 2, standard 3, bracket-arm 4, and bracket-arm head 5, within which is supported a reciprocating and laterally vibrating needle-bar 6, carrying a needle 7. The bed is provided with a forwardly extending work-supporting horn 2^a 35 within which is mounted lower stitch-forming mechanism which cooperates with the needle in the formation of stitches. Inasmuch as the means for actuating the needle and the construction of, and means for actuating the lower stitch-forming 40 mechanism, may be conventional and form no part of the present invention, illustration and description thereof are deemed unnecessary.

The improved button-clamp comprises a supporting arm 8 hinged to a portion of the sewing 45 machine, as for example, by its attachment to an angle piece 9, pivoted, at 10, to a bracket 11 secured to the standard 3. At its forward end the arm 8 has a downturned portion 8^a provided with a seat 8^b adapted to receive any one of a 50 plurality of interchangeable button-supporting feet such, for example, as the feet 12, 13 and 14 shown in Figs. 2, 4 and 5, adapted to hold, respectively, wire-shank buttons x, leather-shank buttons y and self-shank buttons z. 55

The material *m* to which the buttons are to be secured, may be held upon any suitable form of support located beneath the button-supporting feet, such, for example, as the work-supporting blocks 15 and 16 removably and interchangeably mounted upon pins 17 and 18 projecting upwardly from a work-plate 19 secured upon the portion 2^a of the bed 2. The block 15 is adapted primarily for blind-stitch sewing, while the block 16 is adapted for through-and-through stitching with a stay-button. If desired, blocks similar to the block 16 but without the stay-button cavity *s* may be employed. Another form of work-support, which may be used in conjunction with the present improved button-clamp, is shown in Fig. 5. This work-support is similar to that shown in U. S. patent to Lyons, No. 1,654,593, Jan. 3, 1928.

Referring to Figs. 1, 2 and 3, it will be seen that cooperating with the foot 12, to hold the buttons, is an arm 20 provided with a cup-like button-engaging head 20^a adapted to engage the button *x* to hold the shank *x'* thereof in a suitable aperture formed in the foot. As shown in Fig. 2, this head 20^a provides two button-engaging portions 20^b and 20^c which contact with the button at opposite sides of the center thereof, thereby holding the shank of the button in the foot 12 and preventing tipping of the button. Fig. 3 illustrates the line contact between the portion 20^b and the head of the button. A similar line contact is provided by the portion 20^c.

The arm 20 comprises one part of a two-part button-clamping lever which is adjustably mounted, for horizontal movement, on the other part 21, pivotally mounted upon a shoulder screw 22. This screw is secured in the downturned portion 8^a of the clamp-supporting arm 8 and has its forward end, projecting through a slot 20^d formed in the horizontal portion of the arm 20. A nut 23 threaded on the screw 22 serves to clamp the arm 20 to the lever 21 in any desired position of adjustment. The arm 20 is adjustable lengthwise of the lever 21 to compensate for various thicknesses of the button heads. Thus, regardless of the thickness of the heads of the buttons to be attached, full contact may be maintained therewith at opposite sides of the center of the button.

Means is provided for swinging the lever 21, and the arm 20 carried thereby, in a clockwise direction (as seen in Fig. 2) to open the button-clamp, and to swing them in the opposite direction to close the clamp after the button has been inserted. This means comprises an actuating lever 24 pivotally mounted at 25 to a stud 26 carried by the supporting arm 8. The forward end of this lever is formed as a cylindrical finger 27 which projects through a slot 8^c in the portion 8^a and fits between the walls 21^a and 21^b of an inclined slot 21^c formed in a portion 21^d of the lever 21. The lever 24 is normally maintained in the position shown in Figs. 1 and 2 by the action of a coil spring 28 located between the upper surface of the arm 8 and the head 29^a of a tubular nut 29 threaded upon the upper end of a rod 30 connected to the lever 24. The arm 8 and the parts carried thereby are normally held depressed by the action of a spring-pressed plunger 31 as shown in U. S. patent to Lyons, No. 1,583,062, May 4, 1926, but may be swung upwardly about the pivot 18 by suitable treadle-actuated means designated generally as *t*. After the button has been attached, initial upward movement of the button-clamp breaks the thread 75 (as is well understood) and brings the head 29^a

into engagement with the lower wall 4^a of the bracket-arm (see Figs. 1 and 4). Continued upward movement of the clamp causes the lever 24 to be swung downwardly, relative to the arm 8, in opposition to the spring 28. During this movement, the finger 27 is, in effect, moved downwardly and acts upon the wall 21^b of the slot 21^c, thereby causing the button-clamping lever 21, 20 to be swung clockwise, about the pivot 22, to the position indicated in dotted lines in Fig. 4. This releases the button so that it may be removed from the button-clamp and replaced by another button for a subsequent sewing operation. As the clamp is lowered, the spring 28 causes the lever 24 to be swung upwardly, relative to the arm 8, 15 whereupon the end 27 acts upon the wall 21^a of the slot 21^c and thereby turns the lever 21, 20 counter-clockwise to bring the portion 20^a into contact with the button.

Fig. 6 illustrates diagrammatically the means 20 provided for preventing opening of the clamp by movement of the button. In that figure the force exerted by the button on the clamping arm 20 is represented by the arrow *f*. This force tends to turn the lever 20, 21 clockwise about the pivot 25 22. Thus the contact point of the wall 21^a on the finger 27 is moved in an arc *g* and exerts a force on the finger, which force is represented by the line *c* perpendicular to the line *i* intersecting the axis of the pivot 22 and said contact 30 point. The force *c* is the component of a vertically acting force *a* and a horizontally acting force *b*. It will readily be perceived that if either the force *a* or the force *b* is resisted the member 20, 21 cannot be moved. As shown by Fig. 6 the force *b* 35 is resisted by a counterforce represented by the arrow *d* due to the fact that the stationary wall 8^a of the slot 8^c is in contact with the side of the finger 27.

From the foregoing it will be apparent that this 40 clamp is self-locking against movement initiated by the button, while the button-clamping arm is free to be moved by actuation of the lever 24.

Fig. 4 shows an arm 20^e removably secured to the lever 21 in place of the arm 20 of Fig. 2. This 45 arm has a cup-like portion 20^h, which is smaller than the portion 20^a of the arm 20, and which is designed to hold smaller buttons, such for example as the button *y*.

Fig. 5 shows the arm 20 adjusted inwardly on 50 the lever 21 to cause the portion 20^a thereof to engage, by two line contact at diametrically opposite sides of the center of the button, a button having a relatively thin head.

Having thus set forth the nature of the invention, what I claim herein is:

1. A button-clamp for shank-type buttons comprising a supporting arm, a button-supporting foot carried thereby and provided with a button-shank receiving aperture, a button-holding lever pivotally mounted on said supporting arm and adapted to engage the head of the button to hold the shank thereof in said aperture, and means to adjust a portion of said button-holding lever bodily relative to said supporting arm to compensate for variations in thickness of the button-heads.

2. A button-clamp for shank-type buttons comprising a supporting member, a button-support provided thereby and located at one face of 70 the button, a button-holding element carried by said supporting member and adapted to engage the other face of a button to maintain the button in a substantially vertical position and in contact with said button-support, and means to 75

- effect a relative bodily adjustment between said button-holding element and said button-support transverse to a face of the button to provide uniform contact between the button and said element regardless of the thickness of the button. 5
3. A button-clamp for shank-type buttons comprising a supporting arm, a button-support provided thereby, and a two-part button-holding member pivotally mounted on said supporting arm and adapted to engage the head of the button to hold the shank thereof in contact with said button-support, one part of said button-holding member being movable relative to the other part to compensate for variations in the 10 button-heads.
4. A button-clamp for shank-type buttons comprising a supporting member, a button-supporting foot carried thereby and provided with a button-shank receiving aperture, a two-part 15 button-holding lever pivotally mounted on said supporting arm, and spring-actuated means normally urging said lever into contact with the head of the button to hold the shank thereof in said aperture, one part of said button-holding lever being movable relative to the other part to maintain uniform contact between said lever and the button regardless of the thickness of the button-head. 20
5. A button-clamp for shank-type buttons comprising a supporting arm, a button-supporting foot carried thereby and provided with a button-shank receiving aperture, a button-holding lever pivotally mounted on said supporting arm, and a cup-like button-engaging portion 25 carried by said lever adapted to engage the head of the button at opposite sides of the center thereof to hold the shank of the button in said aperture.
6. A button-clamp for shank-type buttons comprising a supporting member providing a button-support having a button-shank receiving aperture, a two-part button-holding element mounted on said member and including a button-engaging portion adapted to contact with buttons at opposite sides of the center thereof 30 to hold the button-shanks in said receiving aperture, one part of said button-holding element being movable relative to the other part to maintain uniform contact with the button regardless of variations in the button-heads. 35
7. In a sewing machine having a frame and a work-plate, a button-clamp pivoted to said frame, means carried by said frame to tilt said button-clamp about its pivot, said button-clamp comprising a supporting arm, a button-supporting foot secured to said arm and provided with a button-shank receiving aperture, a work-support carried by said work-plate beneath said foot, a button-holding arm pivotally mounted on said 40 supporting arm, means to swing said arm into contact with a button to hold the shank thereof in the aperture in said foot, and means to adjust the position of said button-holding arm bodily relative to said supporting arm to compensate for variations in the thickness of buttons. 45
8. In a sewing machine having a frame, a button-clamp pivoted to said frame, means carried by said frame to tilt said button-clamp about its pivot, said button-clamp comprising a supporting arm, a button-supporting foot secured to said 45
5. A button-clamp receiving aperture, a button-holding lever pivotally mounted on said supporting arm, and having an inclined slot therein, means including an actuating lever pivoted to said arm and having a portion within said slot to swing said button-holding lever in one direction into contact with a button to hold the shank thereof in the aperture in said foot, means actuated by the tilting movement of said button-clamp to swing said lever in the opposite direction to release said button, and means to adjust the position of said button-holding lever bodily relative to said supporting-foot to compensate for variations in the thickness of buttons. 5
9. A button-clamp comprising a pivotally mounted supporting arm, means to raise said arm, a button-supporting foot carried thereby, a button-holding lever carried by said supporting arm and cooperating with said foot to hold a button, means actuated by the upward movement of said supporting arm to swing said button-holding arm out of contact with the button, and means to lock said button-holding arm against movement under the influence of the button. 10
10. A button-clamp comprising a supporting arm provided with a vertically arranged slot, a button-supporting foot carried by said arm, a button-holding lever carried by said supporting arm and cooperating with said foot to hold a button, said lever being provided with an inclined slot a portion of which is aligned with the slot in said supporting arm, an actuating lever pivotally mounted on said supporting arm and having a finger projecting through and engaging the walls of said slots, means to move said lever in one direction to cause said finger to act upon one of the walls of said inclined slot to swing said button-holding lever into engagement with a button in said supporting foot, and means to move said lever in the opposite direction to cause said finger to swing said button-holding lever out of engagement with said button, said slots and finger being so constructed and arranged as to lock said button-holding lever against movement under the influence of said button. 15
11. A button-clamp comprising a supporting member, a button-support carried thereby, a button-holding member carried by said supporting member and cooperating with said button-support to hold a button, means to move said button-holding member into contact with the button, and means to lock said button-holding member against movement under the influence of the button. 20
12. A button-clamp comprising a supporting member, a button-support carried thereby, a two-part button-holding lever carried by said supporting member and cooperating with said button-support to hold a button, means to move said button-holding lever into contact with the button, means to lock said button-holding lever against movement under the influence of the button, and means to adjust one part of said button-holding lever relative to the other part and to said button-holder to compensate for variations in thickness of buttons to be held in said button-clamp. 25

MICHAEL McCANN.
